UNITED STATES PATENT OFFICE.

SIDNEY J. STAPLES, OF WEST NEW YORK, NEW JERSEY, ASSIGNOR TO AUTO PNEUMATIC ACTION COMPANY, A CORPORATION OF NEW YORK.

GRAND PLAYER-PIANO.

1,121,774. Specification of Letters Patent. Patented Dec. 22, 1914.

Application filed November 1, 1912. Serial No. 728,979.

To all whom it may concern:

Be it known that I, SIDNEY J. STAPLES, a citizen of the United States, residing at West New York, in the county of Hudson and State of New Jersey, have invented a new and useful Grand Player-Piano, of which the following is a specification.

This invention relates to an improvement on the grand player piano, and particularly to an improvement on the grand player piano shown, described and claimed in an application for patent filed of even date herewith, Serial No. 728,990 in the name of William J. Keeley. In said application for patent is shown a grand player piano having a tracker and sheet supporting mechanism arranged so that when in operative position, the tracker will stand above the piano casing; combined with means for lowering the parts vertically into inoperative position within the piano casing. I modify this mechanism by arranging the means which is employed to raise and lower the tracker and sheet manipulating mechanism so that connections can be extended therefrom to swing the pedals synchronously into and out of operative position.

The parts are arranged so that the pedals will be moved to operative position when the tracker and sheet manipulating mechanism are moved to operative position, and so that the pedals will be folded into inoperative position when the tracker and sheet supporting mechanisms are moved to inoperative position. By this arrangement, both operations can be simultaneously performed by manipulating a single handle.

The improvement is shown in the accompanying drawings in which,

Figure 1 is a sectional elevation showing the parts in operative position, Fig. 2 is an elevation showing the pedals folded into inoperative position, Fig. 3 is a plan of the link work extending from one of the pedals, and Fig. 4 is a front elevation of the parts shown in Fig. 1.

Referring to said drawings and in detail, A designates the casing, C the front board, and D the keys of a grand piano. Housed within the piano is an L-shaped support or bed E. A frame 13 is fitted to slide on the vertical part of the bed E by means of suitable guides 19 which engage ways 20. The frame 13 carries vertical boards F-F be-

tween which is arranged the tracker T, and said boards also carry journals in which the music spool G can be arranged and carry journals which support the take-up spool H, these parts being arranged so that a perforated note-sheet J can be drawn over the tracker T to operate the player mechanism. These parts thus far described are arranged substantially as shown in said application for patent and are designed so that the tracker and sheet supporting mechanism when in operative position will stand above the piano casing, and so that when in inoperative position, the same will be lowered down into the piano casing.

The mechanism for raising and lowering the tracker and sheet supporting mechanism is arranged as follows: A shaft 30 is journaled in bearings secured to the under side of the key bed and on the ends of this shaft are secured arms 31-31, which arms connect by links 32-32 to pivots on the under side of the frame 13. A longitudinally extending shaft 33 is also journaled in bearings secured to the under side of the key bed and is connected to rotate the shaft 30 by means of miter gears 34-35. An operating handle 36 is fastened on the forward end of the shaft 33. By swinging the handle to the position shown in the figures, the frame 13, and therefore the tracker and sheet supporting mechanism, will be elevated to operative position, while by turning the same around substantially 180 degrees, the frame 13, and therefore the tracker and sheet supporting mechanism, will be lowered into inoperative position within the piano casing.

The arms 31 stand in vertical position when the frame 13 and the tracker and sheet supporting mechanism are in operative position and thus the parts carried by the frame 13 will be firmly held in their raised position.

P designates the pedal frame or casing extending down from the key bed of the piano. In the lower end of this frame are arranged the usual pedals by which the expression of the piano is controlled when the same is played manually. The lower part of the pedal frame P is recessed or made in box-like structure to contain the two operating pumping pedals Q-Q. A cover board R is hinged to the bottom of the pedal frame and the pedals Q-Q are hinged to this cover board. These parts are arranged so that

when the pedals are swung or folded up into inoperative position within the pedal frame, the cover board R covers up the openings.

A shaft 37 is secured in blocks within the 5 pedal frame and the operating link work extending from the pumping pedals is pivoted on this shaft. The operating link work for each pedal is constructed as follows:—A 10 forwardly extending arm 38 is pivoted on said shaft 37 and carries a roller 39 at its forward end, against which one of the 15 pedals Q bears. A rearwardly extending rock arm 40 is also pivoted on said shaft, the end of this arm being bifurcated and the 20 arm 38 being fitted therein. The arm 40 carries a lug or stop 41 against which the inner end of the rock arm 38 bears. The arm 40 is connected by a link 42 and other suitable connections to one of the operating 25 pumps.

When the pumping pedals are in operative position, as shown in Figs. 1 and 4, each 30 set of arms 38 and 40 will form in effect a compound folding rock arm whereby the movement of the pedals will be transmitted to the links 42. When the pedals are swung up into the pedal frame the rock arms 38 of the two pedals will turn around on the shaft 37 and the inner ends of the same will move 35 away from the lugs 41 on the bifurcated arms 40. Thus the pedals can be folded up into the pedal frame without disturbing their operative connection to the pumps.

An arm 43 is fastened to the side of the 40 board R and the same is connected by a link 44 to the pivot connecting the right-hand arm 31 and link 32. By this arrangement, when the handle 36 is manipulated to lower the frame 13, and the tracker and sheet supporting mechanism, the arm 43 will rotate in the direction indicated in the dotted line in Fig. 1 and this will swing up the cover board R to the vertical position shown in Fig. 2 and will thus swing or fold the pumping 45 pedals up into the pedal frame or casing. Again when the handle is manipulated to lift the frame 13 and the tracker and sheet supporting mechanism to operative position, the cover board R will be swung outwardly 50 and the pumping pedals will be brought out to operative position. Thus a manipulation of the handle in one direction brings the tracker and sheet supporting mechanism and pumping pedals to operative position, 55 and a manipulation in the other direction lowers the tracker and the sheet supporting mechanism into inoperative position and at the same time folds the pumping pedals up into the pedal frame. It also will be noticed 60 that the weight of the cover board R and the pumping pedals is arranged to act to counter-balance the weight of the frame 13 and the parts carried thereby, whereby the manipulations previously described can be 65 easily performed.

The details and arrangements herein shown and described may be greatly varied by a skilled mechanic without departing from the scope of my invention as expressed in the claims.

Having thus fully described my invention, 70 what I desire to secure by Letters-Patent is:—

1. A grand player piano having, in combination, a piano casing, a tracker and sheet 75 supporting mechanism mounted for vertical movement into and above said casing, means for vertically moving said mechanism into operative and inoperative position, pumping 80 pedals, a folding support for said pedals, and parts connected to said means and said support by which the pedals are moved to operative position when the tracker and sheet supporting mechanism is vertically raised above the casing and by which the 85 pedals are moved into inoperative position when the tracker and sheet supporting mechanism is lowered to inoperative position within the casing.

2. A grand player piano having, in combination, a piano casing, a pedal frame, a 90 tracker and sheet supporting mechanism vertically movable into position within or above said casing, a handle, and means operable thereby for raising and lowering the 95 tracker and sheet supporting mechanism into operative or inoperative position, pumping pedals, a folding support for said 100 pedals, and parts connected to said means and said folding support by which the 105 pedals are moved into operative position when the tracker and sheet supporting mechanism is raised above the casing to operative position and by which the pedals are folded into the pedal frame when the tracker 110 and sheet supporting mechanism is lowered to inoperative position within the casing.

3. In a grand player piano, the combination of the piano casing, a tracker and sheet supporting mechanism, a pedal frame, 110 pumping pedals, a folding support therefor and means for moving said mechanism and pedals into operative and inoperative positions, comprising a shaft, arms secured thereto, links extending therefrom to the 115 tracker and sheet supporting mechanism, a link extending therefrom to the pumping pedals, a longitudinally extending shaft, miter gears connecting said shafts, and an operating handle on said longitudinally extending shaft.

4. In a grand player piano, the combination of the piano casing, a tracker and sheet supporting mechanism, a pedal frame, a cover board pivoted thereto, pumping pedals 125 pivoted to the board, compound operating links extending to the pumping pedals, and means for moving said mechanism and pedals to operative and inoperative position, comprising a shaft having arms, links ex- 130

tending therefrom to the tracker and sheet supporting mechanism, and a link extending therefrom to the cover board, and means for rotating said shaft, the weight of the cover board and pedals being effective to substantially counter-balance the weight of the tracker and sheet supporting mechanism.

In testimony whereof I have hereunto set my hand, in the presence of two subscribing witnesses.

SIDNEY J. STAPLES.
